UNITED STATES PATENT OFFICE

EUGENIO PEDRINI, OF TURIN, ITALY

CARBURETOR FOR INTERNAL-COMBUSTION ENGINES

Application filed March 14, 1929, Serial No. 347,050, and in Czechoslovakia and Germany February 19, 1929.

This invention relates to improvements in carburetors for internal combustion engines the object of which is to effect a preliminary fuel and air mixture before the fuel is admitted into the suction pipe as well as a compensating action on the fuel delivery for the purpose of ensuring a practically constant composition of mixture at any number of revolutions of the engine.

10 According to my invention the mixing and compensating appliances comprise a spray nozzle, which instead of extending directly into the usual suction pipe of the carburetor ends by a delivery pipe, conical in shape and provided with one or more circular rows of holes; this delivery pipe reaches into a suitable chamber having on the same axis as the spray nozzle other perforated cones and communicating with an outer air intake and with 20 the top of the spray nozzle in proximity to its restricted portion, the chamber opening above into the main suction pipe of the carburetor.

This chamber and its air pipes serve for 25 mixing the fuel delivered by the spray nozzle with air before the fuel reaches the suction pipe where it undergoes a thorough pulverization, and said chamber in combination with the pipes communicating with the outer 30 air intake has a compensating action on the delivery of fuel from the spray nozzle which is automatically exerted when the number of revolutions of the engine varies.

At low engine speeds the chamber is partly 35 filled with liquid fuel so as to provide a larger evaporating surface in order to allow for the lower suction and thus gives a mixture practically equal to the normal working mixture. At normal engine speed the chamber practically contains no fuel and through 40 the communication with the outer air which acts directly also upon the spray nozzle a fall takes place in the underpressure acting on top of the spray nozzle which results in a braking action on the fuel delivery and in a poorer mixture at high engine speeds in opposition 45 to the usual carburetors where in such cases the mixture is always too rich with an unnecessary consumption of fuel.

50 Besides the main spray nozzle my car-

buretor is provided with an auxiliary spray nozzle for the minimum engine speed which provides for the preliminary mixing of fuel with air as described in connection with the main spray nozzle as well as for adjustment on the fuel and air inlet.

The accompanying drawing shows diagrammatically a constructional form of the object of this invention.

Figure 1 is a cross section of the carburetor. 60
Figure 2 is a sectional view of a detail on an enlarged scale.

Referring to the drawing the carburetor is cast into a piece comprising the constant level chamber 1, the conduit 2 for the main spray nozzle and the suction pipe 3 in which a Venturi tube 4 of the usual type is arranged. 65

The constant level chamber may be of the known type and form; in the example shown a float 5 is arranged in the chamber 1 and is provided with a central bore for a needle 6 provided with a collar 7 to which the usual weights 8 are articulated. The cover 9 of the float chamber 1 is formed with inner projections 10 to which the abovementioned members are connected, and into a lower hole of the chamber 1 is screwed a sleeve 11 with a seat 12 on which acts the valve needle 6 and openings 13 for the fuel which is conveyed to the carburetor through a pipe connected to the collar 14 of the connecting tube 11. 70
75

A conduit 2 is branched from the chamber 1, is threaded at its inner end and connected through a packing 15 with a filter for the main nozzle. This filter consists of an outer casing 16 enclosing a hollow stem 17 screwed at one end on the conduit 2 and carrying at its other end a hexagonal head 18 provided with abutments 19 for connecting the casing 16 tightly to the conduit 2. The hollow stem 17 has 80 transverse holes 20 and a peripheral filter gauze 21 for the fuel. The outer casing 16 is further provided with an upper bored extension for conveying the fuel to the main spray nozzle 23. 85

Past its restricted portion the spray nozzle 23 is again enlarged to a conical shape and forms a distributor 23a provided with holes. In the example shown the distributor is provided with a lower hole 24, a middle hole 25 90 and an upper hole 26.

and an upper row of holes 25 of suitable section and is threaded on its upper edge for screwing thereon in an adjustable manner a frustum-shaped cover 26.

5 The spray nozzle 23 is placed within a chamber 27 that tightly fits on the nozzle at its lower end, is open above and throttled to form a double cone 28 opposite the holes 25. The chamber is provided on one side with an 10 adjusted air intake 29 with which it communicates by a pipe 30 and an opening 31 formed on the throttle ring 28. The air intake 29 also communicates with the hole 24 in the lower portion of the distributor through a 15 pipe 32, a perforated adjusting plug 33 and another pipe 34.

The chamber 1 carries on one side a pipe 37 communicating with a recess 38 cast with the body of the carburetor and communicating 20 through a passage 39 with the suction pipe 3 opposite the throttle valve 40. The recess is screw-threaded above and encloses a tube 41 (Fig. 2) screwed thereon, carrying below an auxiliary spray nozzle 42 for the 25 minimum engine speed and above an air intake 43, both suitably adjusted. Opposite the passage 39 the tube 41 is provided with a groove 44 having a transversal bore.

This carburetor works as follows: On 30 starting the engine when the number of revolutions is at its lowest, the chamber 27 is partly filled with fuel conveyed through the conduit 2 from the chamber 1, and through the filter 21, the conduit 22, spray nozzle 23 and hole 35. Upon previous adjustment of 35 the position of the cover 26 with respect to the throttled portion 28, the underpressure acting on the top of the chamber 27, upon an acceleration of the engine, causes the fuel to 40 rise and to come into contact with the air flowing in through the hole 31, suitably mixing with said air. The mixture now immediately enters the suction pipe 3 and rapidly empties the chamber 27 and the mixture burnt 45 by the engine is rapidly enriched and improves the engine acceleration when the number of revolutions vary.

When the engine has reached a normal i. e. a rather high number of revolutions, the 50 chamber 27 is nearly empty and the fuel delivered by the spray nozzle 23 is subdivided through the holes 25 and 35, comes into contact with the air sucked in owing to the underpressure through the adjusted intake 55 29, mixes with said air and is partly pulverized and conveyed to the Venturi tube 4 already in a finely subdivided state, so that a perfectly uniform gaseous mixture is formed.

60 At the same time air flows through the hole 24 from the intake 29 and besides operating to form the mixture fills the important office of reducing and thus partly compensating the underpressure acting on 65 the top of the chamber 27 with the result of

exerting a braking action on the fuel delivery at high numbers of revolutions of the engine, thereby making the mixture less rich and bringing it to its normal composition.

By suitably adjusting the bore of the air 70 intake 29, of the openings provided in the distributor 23a and the position of the frustum-shaped cover 26 a suitable compensation of the mixture is effected at the various numbers of revolutions of the engine with a considerable economy in the consumption of fuel. 75

It is clear that in order to improve the mixing action of the chamber 27, one or more suitably perforated cones may be provided in the interior of same, for the purpose of a 80 thorough subdivision of the fuel issuing from the spray nozzle.

The minimum speed appliance also ensures 85 an efficient preliminary mixing of fuel with air. For this purpose I carefully choose the bore of the spray nozzle 42 and of the air intake 43 of a suitable diameter and the mixture formed therein is sucked along the passage 39 into the main suction pipe 3 opposite the throttle valve 40.

As the fuel level is above the minimum speed spray nozzle a fuel supply is always stored in the tube 41 for improving starting of the engine.

90 What I claim is:

1. A carburetor for internal combustion engines comprising, in combination with a constant level chamber, a spray nozzle and a Venturi tube, a cone-shaped distributing tube provided with holes at different heights and being an extension of said spray nozzle, a chamber surrounding said distributor and communicating above with the Venturi tube and means for effecting a compensating action on the fuel delivery in order to ensure a 100 practically constant composition of the mixture in the Venturi tube under varying working conditions. 105

2. A carburetor for internal combustion engines comprising in combination with a constant level chamber, a spray nozzle and a Venturi tube, a cone-shaped distributing tube provided at its upper end with a circular 110 row of holes, a chamber open at one end and surrounding said distributor, an adjustable cover closing the upper end of said tube and adjusting the annular opening between said chamber and distributor, a throttle ring in the chamber in correspondence with said circular row of holes and means for ensuring a 115 practically constant composition of the mixture in the Venturi tube under varying working conditions. 120

3. A carburetor for internal combustion engines comprising in combination with a 125 constant level chamber, a spray nozzle and a Venturi tube, a cone-shaped distributing tube provided at its base with a radial hole and with a radial hole in a middle point and a circular row of radial holes on its upper por- 130

tion, a chamber open at one end and surrounding said distributor, a throttle ring in the chamber at the level of the circular row of radial holes of the distributor, a cover closing the upper end of said distributor and adjusting the annular opening between said throttle ring and the distributor an air intake suitably adjusted communicating with said chamber at the level of the circular row of radial holes of the distributor and means for reducing the underpressure in the upper portion of said chamber during the high-speed working.

4. A carburetor for internal combustion engines comprising in combination with a constant level chamber, a spray nozzle and a Venturi tube, a cone-shaped distributing tube provided at its base with a radial hole and with a radial hole in a middle point and a circular row of radial holes on its upper portion, a chamber open at one end and surrounding said distributor, a throttle ring in the chamber at the level of the circular row of radial holes of the distributor, a cover closing the upper end of said distributor and adjusting the annular opening between said throttle ring and the distributor, an adjusted air intake communicating with said chamber at the level of the circular row of radial holes of the distributor and a conduit connecting said adjusted air intake with the radial lower hole of said distributor.

5. A carburetor for internal combustion engines comprising in combination with a constant level chamber, a spray nozzle and a Venturi tube, a cone-shaped distributing tube provided with a radial hole at its base, with a radial hole in a middle point and with a circular row of radial holes at its upper portion, a chamber open at one end surrounding said distributor, a throttle ring in the chamber at the level of the circular row of radial holes of the distributor, a cover closing the upper end of said distributor and adjusting the annular opening between said throttle ring and the distributor, an adjusted air intake communicating with said chamber at the level of the circular row of radial holes of the distributor, a conduit connecting said adjusted air intake with the lower radial hole of said distributor and an adjusting plug in said conduit.

6. A carburetor for internal combustion engines comprising in combination with a suction pipe, a throttle valve, a Venturi tube in said pipe, a constant level chamber, a spray nozzle, a cone-shaped distributing tube provided with a radial hole at its base, a radial hole in an intermediate point and a circular row of radial holes on its upper portion, a tube open at one end and surrounding said distributor, a throttle ring in the chamber at the level of the circular row of radial holes of the distributor, a cover closing the upper end of said distributor and adjusting

the annular opening between said throttle ring and the distributor, an adjusted air intake communicating with said chamber at the level of the circular row of radial holes of the distributor, a conduit connecting said adjusted air intake with the radial lower hole of said distributor, a recess, a conduit connecting said recess constantly with the float chamber, a tube fixed in said recess, a spray nozzle at one end of said tube, an adjusted air intake at the opposite end of said tube and a conduit connecting the tube bore with the suction pipe opposite the throttle valve.

In testimony that I claim the foregoing as my invention, I have signed my name.

EUGENIO PEDRINI.
